ANIMAL SHELTER FOR A DOG OR THE LIKE

Thayer J. Hoff, 6817 N. 22nd Place,
Phoenix, Ariz. 85016

Filed Dec. 7, 1970, Ser. No. 26,383

Term of patent 14 years

Int. Cl. D30—02

U.S. Cl. D30—1

FIG. 1

FIG. 2

FIG. 4

FIG. 3

FIG. 1 is a front perspective view of an animal shelter for a dog or the like showing my new design; FIG. 2 is a front elevation thereof; FIG. 3 is a rear elevation thereof; FIG. 4 is a side elevation thereof opposite that shown in FIG. 1; and FIG. 5 is a bottom plan view thereof.

I claim:

The ornamental design for an animal shelter for a dog or the like, substantially as shown.
